UNITED STATES PATENT OFFICE

JOHN ROBERTS MITCHELL, OF TRENTON, NEW JERSEY

BASE FOR THREAD PACKAGES

Application filed January 21, 1930. Serial No. 422,471.

This invention relates to a support for thread packages as used in the textile industry, and has special reference to the provision of a base or cup to be placed under a 5 thread cone, or any other type of thread package.

It is well-known by those in the textile art that some means must be provided to absorb or drain off the excess moisture which collects 10 at the bottom of the thread packages in the damp or moistening boxes used in connection with silk hosiery machines.

Felt is now being used to attain this result but has various disadvantages. It soon becomes saturated, thereby rendering it useless and because of the great amount of moisture to which it is subjected, it deteriorates 15 very rapidly, thereby causing a loss of time and requiring frequent replacements.

The object of this invention is to provide 20 a means whereby a thread package such as a silk cone is supported and the moisture is drained from the bottom of the same without experiencing the disadvantages referred to 25 in the preceding paragraph.

To attain this object and others that will appear in the following description and illustrations, a base or cup, frustro-conical in shape, is made of vitreous material such as 30 porcelain and placed under the silk cone. A cone base of such a material and shape is very durable and presents a great improvement over the present art.

A better understanding of this invention 35 will be obtained from the following description and illustration in which:

Figure 1 is a side view of the silk cone and cone base, which latter is shown in section;

Figure 2 is a plan view of the cone base; 40 and

Figure 3 is a sectional view of the cone base taken on line 3—3 of Fig. 2.

Referring more particularly to the drawing, the numeral 10 indicates the cone base 45 which is frustro-conical or saucer shaped, its larger diameter forming the upper part and its smaller diameter forming the lower part. The base 10 is formed with an upwardly extending flange or rim 11 at its outer periphery. A hollowed out portion or recess 12 is

formed in the central part of the upper face of the base 10. A hole or aperture, indicated by the numeral 13, is cut through or formed in the center of the base 10. The portion of the upper surface of the base which surrounds 55 the recess 12 is tapered downwardly toward the center of the base 10 as shown at 14 in the drawing. Outside of the tapered portion 14 the upper surface of the base is flat, as indicated at 15, which flat surface forms a 60 ledge lying inside the flange 11. Grooves 16 radiating from the center of the base 10 are cut in the top surface of the base and these grooves extend across the inclined portion 14 and the flat portion 15 of the upper surface. 65 A thread cone or cap C is shown in Figure 1 supported on the ledge 15 of the base 10, and a spindle 17 of the usual type projects upwardly through the base 10 and the thread cone C. 70

This device performs the following function: The base 10 supports the thread cone C and any moisture which collects upon the base is conducted or drained away by the grooves 16 and the tapered portion 14 to the 75 center of the base and down through the hole indicated at 13 to any suitable receptacle provided therefor.

It is to be understood that the invention is not limited to the specific arrangement 80 shown and described but may be embodied in other forms and used to support other types of thread packages.

Having thus described the invention, what is claimed as new and desired to be secured 85 by Letters Patent is:

1. A base of vitreous material adapted to be placed under a damp thread package in a textile machine, said base having a recess formed on its upper side at substantially 90 the center thereof, a rim or flange extending upwardly at its outer periphery, and grooves formed in its upper surface, said grooves leading inwardly toward said recess.

2. A base of vitreous material adapted to 95 be placed under a damp thread package in a textile machine, said base being provided with grooves adapted to drain off the moisture which collects thereon.

3. A base of vitreous material adapted to 100

be placed under a damp thread package in a textile machine, said base being provided with radial grooves adapted to drain any moisture which collects thereon toward the central portion of said base, said base being perforated at said central portion.

4. A base of vitreous material adapted to be placed under a thread package in a textile machine, said base having an upper surface on which the package is adapted to rest, said surface having grooves therein for conducting away moisture which collects thereon.

10 5. A structure as specified in claim 4, having a flange surrounding and projecting above said upper surface.

15 6. A base of vitreous material adapted to be placed under a damp thread package in a textile machine, said base having a depression formed on its upper side at substantially the center thereof, said base also having a substantially horizontal ledge extending outwardly from the margin of said depression and a rim or flange surrounding said ledge 20 and extending upwardly therefrom.

25 In testimony whereof I hereunto affix my signature.

JOHN ROBERTS MITCHELL.
